UNITED STATES PATENT OFFICE.

GEORGE W. HAGAN, OF GUIDEROCK, NEBRASKA.

MAIL-BUNDLING DEVICE.

SPECIFICATION forming part of Letters Patent No. 723,381, dated March 24, 1903.

Application filed August 11, 1902. Serial No. 119,315. (No model.)

To all whom it may concern:

Be it known that I, GEORGE W. HAGAN, a citizen of the United States, residing at Guiderock, in the county of Webster and State of Nebraska, have invented a new and useful Mail-Bundling Device, of which the following is a specification.

This invention relates to mail-bundling devices.

10 The object of the invention is in a ready, simple, thoroughly feasible, and practical manner to facilitate the distribution of mail in rural deliveries and to reduce the liability of making mistakes to a minimum.

15 With these and other objects in view, as will appear as the nature of the invention is better understood, the same consists in the novel construction and combination of parts of a mail-bundling device, as will be hereinafter 20 more fully described and claimed.

In the accompanying drawings, forming a part of this specification, and in which like numerals of reference indicate corresponding parts, there is illustrated one form of embodiment of the invention capable of carrying the same into practical operation, it being understood that the elements therein exhibited may be varied or changed as to shape, proportion, and exact manner of assemblage 25 without departing from the spirit thereof.

30 In the drawings, Figure 1 is a view in perspective of the device, showing more particularly the manner in which the bundling of the mail is effected. Fig. 2 is a similar view 35 of the device.

The device of this invention comprises an approximately U-shaped holder 1 and a base 2, rigidly associated with the holder in any manner, as by being riveted or braced thereto, 40 or, if preferred, it may be integral therewith. The holder is composed of two retaining-arms 3, disposed parallel with each other, and a base-piece 4, integral with the arms and preferably disposed at right angles thereto. 45 The base 2 projects a sufficient distance beyond the holder at each side to insure that in operation it will be retained in vertical position, and in this instance it is shown as secured to the upper side of the base-piece 4,

the terminals of the base 2 being slightly bent 50 downward in order to cause them to bear squarely upon the table or other support upon which the holder rests.

The structure as a whole may be constructed 55 of bar metal, preferably rectangular in cross-section, and may be treated in any manner to render it rust-proof.

In the use of the device a strap 5 is loosely placed diagonally across the base, and upon this the mail-matter (designated by 6 in Fig. 60 1) is piled.

The manner in which the mail is bundled by this device is as follows: After the mail has been distributed in the pigeonholes or the like in the order in which it is to be delivered 65 along the route the bundling device is placed upon a table and the assembling-strap placed therein in the manner described. Each family's smaller mail—that is to say, letters and the like—is folded inside of a newspaper, if 70 one is to be delivered to the family, with the name on the paper downward, or if there is no paper the letters and the like will be kept in a group by themselves and disposed between the retaining-arms face down, and this 75 procedure is continued until the holder is filled, when the strap is tightly buckled around the bundle and upon inverting the holder it will be discharged.

In the employment of this extremely simple but thoroughly efficient device the bundling of the mail will be facilitated to such an extent that at least one-half of the time usually employed for that purpose will be saved. Moreover, danger of a pile of mail- 85 matter being thrown down after it has been arranged in order, as from vibrations of the car, will be entirely obviated.

Having thus fully described my invention, what I claim as new, and desire to secure by 90 Letters Patent, is—

1. A device of the character specified, comprising an approximately U-shaped holder, the vertical members of which constitute mail-retaining arms, and a base-piece rigidly 95 secured to the lower portion of the holder and projecting laterally beyond the sides thereof.

2. A device of the character specified, comprising a holder constructed of a piece of metal bent to present a rectangular structure and a base-piece extending at right angles to the vertical members of the holder and riveted to the lower member thereof.

In testimony that I claim the foregoing as

my own I have hereto affixed my signature in the presence of two witnesses.

GEORGE W. HAGAN.
